Attorney.

UNITED STATES PATENT OFFICE.

ARTHUR E. SMALL, OF OAK PARK, ILLINOIS, ASSIGNEE TO UNION METAL PRODUCTS COMPANY, OF CHICAGO, ILLINOIS, A CORPORATION OF DELAWARE.

CAR-COUPLER-POSITIONING DEVICE.

Application filed April 19, 1926. Serial No. 103,067.

This device relates to means for automatically positioning the coupler of a railway car by gravity.

Reference is had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

Two railway cars are automatically coupled together by the movement of their respective couplers forcing the tails of the pivoted knuckle behind gravity locks. The couplers are mounted in the cars so as to permit a limited amount of lateral movement. Such limitation is necessary and essential because if the couplers were allowed to move too far to either side, the couplers of the two cars being coupled would pass each other and not couple, thereby defeating the object of the automatic coupler. The greater the lateral movement of a coupler the less side pressure on the striking casting when the cars are going around curves. This lateral pressure forces the wheel flanges against the rail causing considerable friction and wearing of the rails and wheels.

One of the objects of the invention is to increase the amount of permissible lateral movement of a coupler by providing automatic means for returning the couplers to the longitudinal center of the car or at least close enough thereto so that the automatic couplers will couple. This is what is termed the "coupling range".

It is very often necessary to couple cars on curves and frequently when the radius of the curve is very small, as is common around industrial plants, the couplers of the two cars will be so far out of alignment that they will not automatically couple. Another object of the invention is to automatically bring such couplers within coupling range. The outside rail of a curved track is raised above the inside rail and I provide means whereby the coupler is moved toward the inside of the curve by gravity. This automatic gravity means also returns the coupler to the longitudinal center of the car when the car moves from the curved to the straight part of the track.

In my device the lateral movement be-

tween the coupler and the carrier is eliminated, thus reducing friction and consequent wear on the parts. This is quite an item particularly in sandy countries because couplers are costly and the replacement of a 60 coupler means keeping the car out of service.

Coupler positioning devices reduces the number of broken knuckles and guard arms on couplers which members are frequently bent or broken when the couplers are not 65 within coupling range. Such devices also reduce the number of accidents to trainmen as they are not required to go between the cars and position the coupler preparatory to coupling.

It has been found advantageous to have the coupler support cast integral with the striking casting to obtain a four sided member which reinforces the end sill, draft sill and associated parts and my device is especially adaptable to such a combined casting.

In the drawings:

Fig. 1 shows a typical application of the device to a railway car.

Fig. 2 is a section on line 2—2 of Fig. 1. 80

Figs. 3 and 4 are diagrams showing the preferred form in normal position and extreme lateral position, respectively.

Figs. 5 and 6 show the roller of Figs. 3 and 4 in detail, Fig. 6 being a section on line 6—6 of Fig. 5. 85

Figs. 7 and 8 show a modified form of the construction.

The striking cast or buffer block 2 is attached to the draft sill 3 or other parts of the car body in any suitable manner. The coupler support 4 is attached thereto or preferably cast integral therewith. The coupler 5 rests upon the carriage 6 which engages the support in such a manner as to restrict its movement longitudinally of the car but permits its movement sidewise of the car. This is preferably accomplished by providing a U-shaped support having spaced apart walls 7—8 upon which the carriage 100 moves in one direction but is restricted in its movement longitudinally of the car. This carriage is provided with means 10 to restrict the lateral movement of the coupler relative thereto.

One or more rollers 12 are interposed between the support and the carriage, each of which rollers has a lower curved surface 13 having a rolling engagement with the support, the radius 14 of the curve being greater 110

than half the depth of the roller so that as it rolls to one side it raises the coupler, as shown in Figs. 4 and 8. This is what is called an eccentric roller. These rollers also have a cylindrical upper portion 60 having a journaled engagement 61 with the carriage.

The relative position of the journal and the curved surface may be reversed and still come within the scope of this invention.

10 Some means must be provided to maintain operative relation between the various elements. This may be accomplished by providing projections 16 on the support which engage the opposite ends of the rollers, as

15 shown in Figs. 3 and 4. This result may be accomplished by providing a single projection 18 on the support which engages slots in the rollers, as shown in Figs. 7 and 8 or may simply be a tooth.

20 In an application for patent filed of even date I have disclosed but not claimed certain features which are claimed herein, the co-pending application claiming features and structures forming an independent invention.

25 I claim:

1. In a railway car; the combination of a coupler support, a coupler carriage, and an eccentric quadrant journaled in said carriage with a rolling engagement with the support.

30 2. In a railway car; the combination of

a coupler support, a coupler carriage, and a quadrant journaled in said carriage and having a curved surface with a rolling engagement with the support, the radius of the curved surface being greater than the depth 35 of the quadrant.

3. In a railway car; the combination of a coupler support, a coupler carriage, and an eccentric quadrant journaled in said carriage and having a curved surface with a rolling 40 engagement with the support, said support having means co-acting with said surface to maintain operative relation therebetween.

4. In a railway car; the combination of a coupler support, a coupler carriage, and a 45 quadrant journaled in said carriage and having a curved surface with a rolling engagement with the support, the radius of the curved surface being greater than the depth of the quadrant, said support having 50 projections which engage the opposite ends of the quadrant to maintain operative relation therebetween.

5. In a railway car; the combination of a coupler support, a coupler carriage, and an 55 eccentric quadrant journaled in one of said elements and having a rolling engagement with the other of said elements.

ARTHUR E. SMALL.
